UNITED STATES PATENT OFFICE

160,637

HALF BOOT BOOK END OR SIMILAR ARTICLE

Arthur S. Leitner, Los Angeles, Calif.

Application December 1, 1947, Serial No. 142,894

Term of patent 3½ years

(Cl. D33—1)

To all whom it may concern:

Be it known that I, Arthur S. Leitner, a citizen of the United States, residing in Los Angeles, in the county of Los Angeles, State of California, have invented a new, original, and ornamental Design for a Half Boot Book End or Similar Article, of which the following is a specification, reference being had to the accompanying drawing, forming a part thereof.

The characteristic features of my design reside in the portions shown by means of full lines in the drawing.

I claim:

The ornamental design for a half boot book end or similar article, substantially as shown and described.

ARTHUR S. LEITNER.
